JAM CLEAT

Gerard F. Coderre, 524 Matson Hill Road, and
Marcel W. Coderre, 41 Prospect St., both of
Glastonbury, Conn. 06033

Filed Sept. 26, 1966, Ser. No. 4,031

Term of patent 14 years

(Cl. D54—11)

FIG. 1

FIG. 2

FIG. 3

FIG. 4

FIG. 5

FIG. 6

FIG. 7

FIG. 1 is a perspective view of a jam cleat incorporating our novel design.

FIG. 2 is an end elevational view thereof.

FIG. 3 is a top plan view thereof.

FIG. 4 is a front elevational view of our novel jam cleat.

FIG. 5 is a rear elevational view thereof.

FIG. 6 is a perspective view of a modified embodiment of the jam cleat shown in FIG. 1; and

FIG. 7 is an end elevation thereof.

We claim:

The ornamental design for a jam cleat, as shown and described.
